The side not seen in the drawings is a fac simile to the side seen.

My invention consists in the combination of the several mouldings and ornaments as arranged in the whole stove and is not easily described in words and reference is therefore made to the drawings.

I do not claim any detailed part of the mouldings or configuration.

What I claim as my invention and desire to secure by Letters Patent, is the general combination of the several mouldings and ornaments as arranged together, the whole forming an ornamental Air Tight Cook Stove as herein set forth and described.
